(57) **CLAIM**

The ornamental design for a display apparatus including computer generated icon, as shown and described.

DESCRIPTION

The FIGURE depicts a display apparatus including computer generated icon.

The broken lines in the drawings illustrate unclaimed portions of the computer generated icon and the unclaimed display apparatus, and form no part of the claimed design. The solid outer line forms the edge of the computer generated icon of the claimed design, which is congruent with the inner edge of the frame of the display apparatus.
